UNITED STATES PATENT OFFICE.

ABRAHAM B. LESSER, OF CHICAGO, ILLINOIS.

SAFETY POCKET.

Application filed January 15, 1921. Serial No. 437,467.

To all whom it may concern:

Be it known that I, ABRAHAM B. LESSER, a citizen of the United States, residing at Chicago, in the county of Cook and State of Illinois, have invented new and useful Improvements in Safety Pockets, of which the following is a specification.

This invention relates to safety pockets for wearing apparel and an object of the 10 invention is to provide a pocket, within the ordinary pocket of a garment for containing valuables and to so construct the said safety pocket as to prevent the loss of valuables by "picking" or the malicious removal 15 of the valuables therefrom.

Another object of this invention is to provide a safety pocket which is of practical construction and may be embodied in garments at a comparatively small expense, and 20 further to construct a safety pocket so as to permit free and easy access to the interior thereof by the owner when desired.

A further object of this invention is to provide a closure flap for the safety pocket 25 which is arranged to permit the placing in and removal from the ordinary pocket of articles without in any way interfering with the closure flap of the safety pocket, and also to so arrange the safety flap that it 30 will not attract attention to itself and the safety pocket.

Other objects of the invention will appear in the following detailed description and in the accompanying drawing wherein:

35 Fig. 1 is a view illustrating a side and hip pocket in position in a pair of trousers.

Fig. 2 is an elevation of a side pocket constructed in accordance with this invention and showing the closing flap in open 40 position.

Fig. 3 is an elevation of a hip pocket constructed in accordance with this invention showing the safety flap in a partly open and partly closed position.

45 Fig. 4 is a cross section through a safety side pocket constructed in accordance with this invention and taken on the line 4—4 of Fig. 2.

50 Fig. 5 is a longitudinal section through a hip pocket constructed in accordance with this invention and taken on the line 5—5 of Fig. 3.

55 Referring more particularly to the drawing, both a hip and side pocket for trousers are illustrated and each comprises the usual pocket, which in the hip pocket is indicated

by the numeral 1 while the usual side pocket is indicated by the numeral 2, it being understood that these pockets are made in the usual approved manner, of relatively strong 60 fabric and connected, by stitching, in the usual approved manner to the fabric of which the trousers or article of clothing A is made.

The hip pocket structure comprises the 65 safety pocket within the usual pocket 1 which safety pocket is formed by the piece of fabric 3 stitched around its side and inner edge as indicated at 4 by the stitching which reinforces and connects the parts of the ordinary pocket 1. The upper edge of the piece of fabric 3, which forms the safety pocket, is doubled back upon itself as at 5 and is hemmed as at 6 by the stitching 7 which forms the hem and also serves to attach the folded over reinforcing portions 5 to the main body of the piece of fabric 3. The upper folded over edge of the safety-pocket-forming piece of fabric 3 is free from connection with the pocket 1 and forms the 80 mouth for the safety pocket, which mouth is positioned inwardly of the mouth 8 of the pocket 1. As shown at 9 in Fig. 3 of the drawing, the side edges of the fabric 3, at their portions adjacent the upper edge of the fabric, are not stitched to the pocket 1 by the stitching 4 and these edges are cut at an angle extending inwardly towards the free edge of the piece of fabric 3 to permit spreading of the mouth of the safety pocket 90 to allow free ingress or egress from the safety pocket and prevent the forming of a relatively tight mouth, such as would be formed if the side edges were stitched their entire length to the pocket. 95

A closing flap 10 is stitched to the inner side of the pocket 1 and is preferably formed of the same material as that of which the trousers or article of apparel A is formed, the flap extends from the line of stitching 11 where the fabric of the garment is stitched to the back of the ordinary pocket 1 giving the outward appearance of the usual decorative piece of fabric which extends into all pockets to hide the fabric of which the pocket is made, as this fabric is usually of different color and texture than the fabric of which the wearing apparel is made. 105

The closing flap 10 has its ends cut at an angle as shown at 12 to facilitate fastening and unfastening of the flap and also insertion of the flap into the ordinary pocket 1, 110

however it will be noted by referring to the right hand side of Fig. 3 of the drawing that the closing flap 10 overlaps the upper corners of the upper portions of the piece 5 of fabric 3. Fasteners 13 of any approved type, such as snap fasteners, button and button hole, or the like are carried by the flap 10 and piece of fabric 3 for fastening the flap 10 in a safety-pocket-closing position. 10 The fasteners 13 are arranged inwardly of the ends of the flap and in proper spaced relation to each other and the center of the flap so that when they are fastened the flap cannot be raised sufficiently to permit the 15 insertion of an article into the pocket or the withdrawal of an article therefrom.

The construction of the side pocket is similar to the construction of the hip pocket, the safety side pocket being formed of two 20 pieces of fabric stitched together and to the pocket 2 along its upper, lower and inner edges while the forward edge of one piece of the fabric forming the safety pocket is also stitched to the pocket 2 leaving the 25 forward edge of the other piece of fabric forming the safety pocket free from connection to the pocket 2. The upper end of the free edge 16 of the pocket 15 is cut at an angle as shown at 17 so as to permit 30 spreading of the mouth of the safety pocket sufficiently to allow the free insertion into or removal from the safety pocket of desired articles and the forward or outer free edge of the fabric 15 of which the safety 35 side pocket is formed curves outwardly towards the forward edge of the ordinary side pocket 2 as shown at 18 in Fig. 2 of the drawing, at its lower end so as to prevent small articles, such as coins from falling out 40 of the pocket. The closure flap 19 of the side pocket structure is stitched to the inner surface of the rear piece of fabric of which the pocket 2 is formed at its forward edge and overlaps the forward folded over edge 45 portion 20 of the fabric 15, as clearly shown in Fig. 4 of the drawing. The upper end of the flap 19 is formed to overlap the major portion of the angled corner 17 of the fabric 15 to prevent the contents of the safety 50 pocket from falling therefrom in case the trousers or article of apparel is turned upside down. The fastening structure 21, which may be of any approved type, such as snap fasteners, button and buttonhole, or the like, is placed intermediate the ends of the 55 closing flap 19 so as to prevent opening of

the closing flap sufficient to permit the insertion into or withdrawal from the safety pocket of articles, without unfastening the fasteners 21.

From the foregoing description taken in connection with the accompanying drawings it will be apparent that safety pockets for articles of wearing apparel have been devised which are practical in construction and consequently can be manufactured economically, which safety pockets will prevent "picking" of the wearer's pockets or the malicious removal of their contents as well as prevent the loss of small change, purses or valuable articles when the trousers are hung up on trouser hangers or upside down and, while in the foregoing description and drawing the pockets are disclosed as used in men's trousers it is to be understood that the said safety pockets may be employed in women's coats, skirts, men's coats, or in fact any place where it is desired to provide safety pockets, without departing from the spirit of this invention.

It is, of course, to be understood that the invention may be constructed in various other manners and the parts associated in different relations and, therefore, I do not desire to be limited in any manner except as set forth in the claim hereunto appended.

Having thus described my invention what I claim is:

In a garment, the combination with a 20 pocket, of a safety pocket therein, having its mouth opening inwardly of the mouth of the first named pocket, said safety pocket and first named pocket being of equal width and the side and inner edges of said safety 25 pocket being stitched to the garment by stitching of the said first named pocket, the side edges of the safety pocket at the mouth thereof being cut at an angle which extends inwardly from the sewed edges to the free 30 edge whereby to form free edges permitting spreading movement of the mouth of the safety pocket when in use, a closing flap within said first named pocket to form a closure for the mouth of the safety pocket, 35 said closure flap having its edges at an angle and overlapping the free edge of the safety pocket and means for detachably connecting said flap to the body of the safety 40 pocket.

In testimony whereof I affix my signature.
ABRAHAM B. LESSER.
